UNITED STATES PATENT OFFICE.

WILLIAM HENRY McCAFFREY, OF BIRMINGHAM, ALABAMA, ASSIGNOR OF ONE-HALF
TO J. A. MEADOWS, OF BIRMINGHAM, ALABAMA.

CAR COUPLER.

Application filed October 30, 1920. Serial No. 420,703.

To all whom it may concern:

Be it known that I, WILLIAM H. McCAFFREY, a citizen of the United States, residing at Birmingham, in the county of Jefferson and State of Alabama, have invented a new and useful Car Coupler, of which the following is a specification.

This invention relates to couplers for railway cars, one of its objects being to provide means whereby when two or more cars are coupled together one or more conduits extending through the cars will at the same time be coupled together automatically, thus doing away with the separate hose couplings which have heretofore been generally used where trains of cars are provided with air brakes, steam pipes and the like.

Another object is to combine with a coupler of the ordinary Janney type means for automatically joining together the units of a pipe line carried by a train of cars.

A still further object is to provide a structure of this character which is practically leakproof and which will automatically close the pipe lines at the couplers when the cars are uncoupled but which will be automatically opened when the cars are coupled together so as to establish communication between the corresponding pipes on the cars of the train as soon as the coupling of the cars is effected.

A still further object is to provide means whereby the ports at the ends of the pipes and which open through the couplers are caused positively to register when the cars are coupled and are held against relative movement so as to insure proper communication between the pipes while the coupled cars are in motion.

A still further object is to so connect the pipe lines to the couplers as to allow said couplers to have movement relative to the car, as ordinarily, without necessitating the use of flexible hose.

Another object is to provide the ports in the couplers at the ends of the pipe lines with pistons or plungers of novel form having means for automatically shifting them when the cars are uncoupled so as to cut off the escape of air at the ports, said pistons being shifted when the cars are coupled together so as to automatically open the ports when the plungers on the opposed couplers come together.

Another object is to provide valves for

controlling the flow of air to and from the ports and which are automatically shifted by the opening and closing of the knuckles of the couplers, the casing of the valve being connected in any manner desired to the draw head so as to be maintained constantly in proper relation to the coupler.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a front elevation showing the coupler closed.

Figure 2 is a front elevation showing the coupler open.

Figure 3 is a view partly in side elevation and partly in section of a coupler.

Figure 4 is a section on line 4—4, Figure 3 and showing two couplers connected.

Figure 5 is a detail view of the combined piston and plunger.

Figure 6 is a section on line 6—6, Figure 1.

Figure 7 is a section through the valve.

Figure 8 is a horizontal section on line 8—8, Figure 7.

Referring to the figures by characters of reference 1 designates the ordinary head of a Janney car coupler having a knuckle 2 of the usual configuration, this knuckle being mounted on a pivot pin 3 which is located at the usual place in the coupler head but instead of being freely mounted within the head and knuckle the pin 3 is connected to the knuckle in any suitable manner so that when the knuckle swings to open or closed position the pin 3 necessarily rotates. The lower end of the pin is provided with a flattened face and projects into a coupling sleeve 4 fastened thereto in any manner desired and which serves to connect the pin to the stem 5 of a valve 6. This valve, which is tapered, is mounted for rotation within a casing 7 suitably secured to the bottom of the head 1 so as to be rigid therewith. The

95

100

105

110

valve has a threaded stem 8 projecting downwardly therefrom through the bottom of the casing 7 and which is engaged by a suitably secured nut 9 so as to hold the parts 6 properly assembled.

Brackets or the like indicated at 10 are connected to the draw bar 11 of the coupler and support a pipe section 13 which is connected by a universal joint 14 to a short pipe 10 section 15 which, in turn, is connected by a universal joint 16 to a pipe section 17 opening into the valve casing 7. A portion of the main pipe of the pipe line carried by the car to which the coupler is connected has 15 been indicated at 18 and is connected by a suitable universal joint 19 to a short pipe section 20 which, in turn, is connected by a universal joint 21 to the pipe section 13. Thus it will be seen that while the pipe 18 is 20 fixed relative to the car body the coupler head 1 and the parts connected thereto are free to move relative to the car body, as ordinarily, and the pipe connection between the valve casing 7 and the pipe 18 will be 25 maintained intact and will in no way interfere with the relative movements of the coupler heads and the car body.

The valve 6 can be of any construction preferred but is preferably made hollow 30 with opposed ports 22 and 23 therein and with an interposed vent port 24. When the knuckle of the coupler is closed the port 22 will communicate with the pipe section 17 and the port 23 will communicate with a 35 short pipe section 25 extending from the casing 7. When the ports are thus located the vent port 24 is closed by the wall of the casing 7. When the knuckle 2 is moved to open position, however, the pin 3 moving 40 with the knuckle will rotate the valve so as to close the inlet port 22 and open communication between the vent port 24 and an opening 26 formed in the casing 7, the port 23 remaining in communication with the valve 45 so that air or other fluid under pressure will be free to flow from said port 23 through the valve and to the external atmosphere.

The knuckle 2 is provided in its free vertical edge with tapered notches 27 and 50 formed on the inner side of the knuckle at points remote from the notches 27 are superposed tapered lugs or ribs 28 so that when two couplers are brought together with the knuckles interlocking in the usual way, the 55 lugs 28 on each knuckle will project into the notches on the opposed knuckle and thus hold the two coupler heads against relative up and down movement.

Formed within each of the knuckles of 60 the car coupler is an upwardly extending bore 29 having a short pipe section 30 extending downwardly therefrom and having a leakproof jointed connection 31 with a nipple 32 which extends into a cap 33 65 mounted on a socket member 34. The short

pipe section 25 heretofore referred to opens into this socket member 34 and it will be noted that the said member has a dished seat 35 provided with a cup-shaped washer 36 on which the rounded apertured end of the nipple bears. Suitable packing, in the form of any desired arrangement of washers 37 or the like is provided under the cap 33 so as to prevent leakage. In other words 70 the connection between the pipe 30 and the socket member 34 is such as to permit the knuckle 2 to swing relative to the coupler head without permitting escape of air or other fluid under pressure.

The upper end of the bore 29 is intersected by a bore 38 which opens through the inner face of the knuckle 2 and also has its outer end counterbored, as at 39 and opening through a boss 40 on the outer face of the knuckle. The outer end of the counterbore 80 is normally closed by a screw plug 41 having an inwardly projecting stud 42 on its inner face. The inner end of the counterbore 39 forms an annular shoulder 42' and this shoulder constitutes a seat for a series of coiled 85 springs 43 which thrust outwardly against the head 44 of a plunger 45. This head 44 is provided with any suitable packing, such as an expansion ring 46 so as to provide a leakproof slidable connection or contact between the head 44 of the plunger and the wall of the counterbore 39. The outer end of the plunger has a projecting boss 47 adapted to come against the stud 42 and be held normally in contact therewith by the 90 springs 43, the two bosses serving to hold the head 44 sufficiently spaced from the plug 41 to provide an air chamber 48. This air chamber communicates with the bore 29 through one or more by-passes 49.

The plunger 45 has another smaller head 50 working within the bore 38 between bore 29 and the inner face of the knuckle 2 and this head is preferably provided with an expansion ring 51 similar to the ring 46 and which normally bridges and closes the end of bore 29, it being held there by the springs 43. An annular flange 52 is provided on the plunger and is slidably mounted in the bore 38 between bore 29 and the counterbore 39 100 and this flange may likewise be provided with an expansion ring or other form of packing.

The plunger extends beyond the head 50 and toward the inner face of the knuckle 2, there being an annular flange 54 on this projecting portion of the plunger which is seated within a nipple 55 formed of rubber or the like and which nipple projects beyond the inner face of the knuckle 2 and extends 110 around and moves with the plunger. That portion of the plunger between the flange 52 and that end of the plunger within the nipple 55 is hollow and a number of apertures 115 indicated at 56 are provided in the wall of 120

the plunger between the flange 52 and the head 50.

Extended from the lower portion of each of the knuckles 2 is a lifting tongue 57 having an inclined surface. These tongues constitute deflecting cams and are so positioned that should one of the couplers be at a lower level than the other coupler it will, when moved toward the other coupler, come into engagement with the tongue 57 in the path thereof and this tongue will exert a lifting action upon the lowermost coupler so that it will be elevated to bring the two couplers together at the same level. The knuckles will then swing closed and will be locked automatically, each being provided with a coupling pin such as shown at 53. When the couplings are thus assembled the ribs 28 on each knuckle will project into the notches 27 on the opposed knuckle and the nipples 55 on the two interfitting knuckles will come together and be compressed. When the knuckles are open the pins 3 hold valves 6 in closed positions or, in other words, close communication between the ports 22 and 23. Thus the air within the chamber 48 in each knuckle is free to flow to the atmosphere by way of the ports 49 and 29, pipe 25 and its connections and ports 23, 24 and 26. Consequently the springs 43 hold the plunger in each knuckle pressed toward the screw plug 41 so that communication between the bore 29 and the openings 56 is closed. When the knuckles are moved to closed positions, however, and the opposed nipples 55 pressed together and held, the valve 6 will be automatically opened by the rotation of the pin 3 and air under pressure will pass from the pipe 18 through its various connections to the bore 29 and thence by way of the bypasses 49 into the air chamber 48. The air will press against the head 44 and thrust the plunger longitudinally so as to bring the openings 56 in communication with the bore 29, compress the springs 43, and press the nipples 55 tightly together. Thus air will be free to pass from one knuckle to the other and into the pipe line system of the next car and so on throughout the length of the train. Should one of the knuckles in the train open or become broken the resultant rotation of the pin 3 would result in the rotation of the valve 6 and the cutting off of the pressure.

In the structure illustrated only an air line is employed, the same being for air brake systems and being such as would be used on freight cars. Where the improvements are applied to passenger coaches, however, it would be desirable to multiply the parts so as to couple up the steam and lighting systems in addition to and in the same manner as the described air brake system.

What is claimed is:—

1. In a car coupler the combination with a head and a knuckle mounted to swing rel-

ative thereto, of a tubular plunger slideable within and normally projecting from the inner face of the knuckle, there being a pressure chamber in the knuckle and back of the plunger, a pressure controlling valve 70 operated by the movement of the knuckle relative to the head, and means for directing fluid under pressure from the valve when opened, to the pressure chamber to shift the plunger and place the interior of 75 the plunger in communication with said means.

2. In a coupler the combination with a head and a knuckle mounted to swing relative thereto, of a pressure controlling valve 80 movable with the knuckle to open or close when the knuckle is in its extreme positions, a tubular plunger slideable within the knuckle and opening inwardly through the inner surface of the knuckle, means for guiding 85 the knuckle of an opposed coupler to the same level with the first named knuckle, and means operatively connected to the valve for conducting fluid under pressure from the valve and back of the plunger to shift the 90 plunger and place the interior thereof in communication with the valve.

3. The combination with opposed couplers, each including a head and a pivoted knuckle, said knuckles being movable into 95 interfitting relation to connect the heads, of means upon each knuckle for deflecting the opposed knuckle upwardly to bring the knuckles into the same plane when coupled, cooperating means upon the side portions 100 of the knuckles for holding them against relative up and down movement when coupled, a tubular plunger mounted within each knuckle, a pipe line in communication with the interior of each knuckle, and means operated by the movement of the knuckles to closed or coupling positions for directing pressure into the knuckles to shift the 105 plungers on the opposed knuckles together and to place the interiors of said knuckles 110 in communication with the pipe line.

4. In a coupler the combination with opposed heads and knuckles pivotally connected thereto and movable into interfitting relation, of pipe lines, a bore within each 115 knuckle, means operated by the movement of the knuckles to closed or interfitting positions for establishing communication between the bores and the pipe line, a tubular plunger within each knuckle, means for holding the plunger normally retracted into the knuckle and out of communication with the bore, and means for directing pressure against one end of the plunger when the 120 knuckles are in interfitting relation, to shift the opposed plungers together and to open communication between the plungers and the bores.

5. In a coupler the combination with a head and a knuckle mounted to swing rela-

tive thereto, of a bore within the knuckle and provided with a counterbore, a removable closure for the counterbore, a tubular plunger open at one end and closed at its other end and slideable within the bore and counterbore, cooperating means upon the plunger and closure for spacing them apart to form a pressure chamber, a bore or air passage within the knuckle and communicating with the first named bore and the pressure chamber, yielding means within the counterbore for holding the plunger normally in one extreme position, said plunger having an opening in the wall thereof out of communication with the air passage when the plunger is held in said normal position, a nipple upon the open end of the plunger and projecting from the knuckle, and means operated by the movement of the knuckle relative to the head and into closed or coupling position for directing pressure into the

air passage to shift the plunger longitudinally and place the aperture therein in communication with the air passage.

6. The combination with opposed couplers 25 each including a head and a pivoted knuckle, of hollow plungers slidably mounted within the knuckles and movable into line when the knuckles are placed in interfitting relation, and means operated by the movement 30 of the knuckles to said positions for directing pressure into and through the plungers and for forcing the aligning plungers together to seal the connection therebetween.

In testimony that I claim the foregoing as 35 my own, I have hereto affixed my signature in the presence of two witnesses.

WILLIAM HENRY McCAFFREY.
